UNITED STATES PATENT OFFICE.

EARL SANDUSKY, OF LOS ANGELES, CALIFORNIA.

DESIGN FOR AN AUTOMOBILE-FENDER.

56,770.

Specification for Design.

Patented Dec. 14, 1920.

Application filed January 26, 1920. Serial No. 354,266. Term of patent 7 years.

To all whom it may concern:

Be it known that I, EARL SANDUSKY, a citizen of the United States, residing at Los Angeles, in the county of Los Angeles, State of California, have invented a new, original, and ornamental Design for an Automobile-Fender, of which the following is a specification, reference being had to the accompanying drawing, forming part thereof.

The figure is a perspective view of an automobile fender, showing my new design.

I claim:

The ornamental design for an automobile fender, as shown.

EARL SANDUSKY.

Witnesses:

VIRGINIA BERNINGER,
VERA JONS.
